HAND TOOL FOR PUNCHING, CRIMPING,
CUTTING AND THE LIKE

George J. Filia, Shelton, Conn., assignor to Sargent &
Company, New Haven, Conn.

Filed Apr. 23, 1963, Ser. No. 74,586

Term of patent 14 years

(Cl. D54—13)

Fig.1.

Fig.2.

Fig.3.

Fig.4.

Fig. 5.

FIG. 1 is a side elevational view illustrating a hand tool for punching, crimping, cutting and the like embodying my new design with the handle thereof in a substantially closed position;

FIG. 2 is a top view of the tool with a handle in a closed position;

FIG. 3 is a bottom plan view of the tool;

FIG. 4 is an end elevation of the tool with the handle in a closed position, and

FIG. 5 is a perspective view of the tool.

The parts in broken line in FIG. 1 represent die members and are shown for purposes of illustration.

I claim:

The ornamental design for a hand tool for punching, crimping, cutting and the like, substantially as shown and described.
